Primary Examiner — Jonathan J Han*Assistant Examiner* — Christen Pilar Brown(74) *Attorney, Agent, or Firm* — Banner & Witcoff, Ltd.**(57) CLAIM**

The ornamental design for a shoe, as shown and described.

DESCRIPTION

FIG. 1 is a front perspective photographic view of a shoe showing my new design;

FIG. 2 is a side photographic view thereof;

FIG. 3 is an enlarged view of the design as shown in FIG. 1 with environment removed for clarity purposes; and, FIG. 4 is an enlarged view of the design as shown in FIG. 2 with environment removed for clarity purposes.

The remainder of the shoe shown in a greyed out photographic depiction forms no part of the claimed design. The seven square shaped elements shown in uneven-length broken lines represent eyelets which form no part of the claimed design. The even-length broken lines represent stitching which forms no part of the claimed design.
